UNITED STATES PATENT OFFICE

2,505,297

BURIAL VAULT LATCH

Paul E. Miles, Atlanta, Ga., assignor to Atlanta
Metallic Casket Co., Atlanta, Ga.

Application March 18, 1946, Serial No. 655,098

1 Claim. (Cl. 27—35)

1

This invention relates to improvements in grave vaults, and more particularly to a grave vault base provided with fastening means for a separable hood or cover section.

An object of this invention is to provide a grave vault base with pivoted latch devices carried by the side wall of the base and which co-operate with associated spring means to engage with internal portions of the vault hood to hold the hood securely in place on the base when desired.

Another object of this invention is to provide a grave vault base with latch devices carried by the side walls of the base which are adapted to cooperate with the inner flanges of a vault hood to hold the hood in place when desired and to provide means for unlatching the devices when it is desired to remove the hood.

Still another object of this invention is to provide a grave vault base with latch devices adapted to secure a vault hood in position over the base and a lever protruding from the side walls of the base, the movement of which lever retracts the latches and permits the hood to be removed.

Yet another object of this invention is to provide a grave vault base with latching devices for securing a hood to the base together with spring means for constantly urging the devices to latching position and lever means at each end of the base for moving the latching devices to release position.

To the foregoing objects, and others which may hereinafter more fully appear, the invention consists of the novel construction, combination and arrangement of parts, as will be more specifically referred to and illustrated in the accompanying drawing, but it is to be understood that changes, variations, and modifications may be resorted to which fall within the scope of the invention as claimed.

In the drawing:

Figure 1 is a perspective view of a grave vault base constructed according to an embodiment of this invention.

Figure 2 is a partial section taken on the line 2—2 in Figure 1.

Figure 3 is a fragmentary sectional view taken on the line 3—3 of Figure 1.

Figure 4 is a bottom plan view of the release levers shown in Figure 2, with the base plate removed.

Referring to the drawing, the numeral 10 designates generally a rectangular base for a grave vault embodying this invention.

2

The base 10 is generally of conventional design comprising a flat horizontal top wall 11, depending substantially vertical side walls 12, and an outwardly extending horizontal base flange 13, usually of integral construction and stamped from a single sheet of metal. Base plates 14 are attached to the inside of the base 10 between the side walls 12 substantially at their lower ends. The base plates 14 at each end of the base 10 are formed with semi-circular cut-outs or openings 15 at the transverse median thereof, with the edge of the base plates 14 and the openings 15 abutting the end walls 16. The end walls 16 of the base 10 are formed with centrally located elongated openings 17. The base flange 13, at each end of the base 10, is formed with a centrally located downwardly projecting elongated offset 18. The side walls 12 are formed with rectangular openings 19, through which the latch members 20 are adapted to project. The latch member 20 is stamped or otherwise formed from a piece of sheet metal and includes a pair of elongated side members 21, an outwardly projecting surface 22 disposed between said end plates near the lower end thereof, and an outside surface 22a extends upwardly from the outside of the projecting surface 22 to the upper end of the side members 21. Near the upper end of the side members 21 and extending between the side members a fulcrum or rod 23 is attached.

Inwardly of the opening 19 and attached to the lower side of the top wall 11 a flat spring 24 is secured by rivets or other suitable attaching means 25. The spring 24 attaches to the latch member 20 by extending outwardly over the rod 23 then downwardly and presses outwardly on the inner side of the surface 22a. The downward projecting side members 21 limit the projection of the latch 20 by bearing against the side wall 12.

At each end of the base 10 a support plate 26 is attached to the base 10 by welding or other suitable means. The support plate 26 is substantially S-shaped. One end of the support plate is attached perpendicularly to the lower side of the top wall 11 and extends downwardly about half way between the top wall 11 and the base plate 14, the support 26 is then bent parallel to the wall 11 and extends nearly up to the end wall 16, where it is again bent downwardly and again bent parallel to the wall 11 and in line with the base plate 14 in the opening 15 thereof and attaches to the inside of the end wall 16 above the opening 17.

An elongated lever 27 with an upwardly offset pivot section intermediate the length thereof, is rockably secured to the lower side of the support 26 between the support 26 and the base plate 14. One arm of the lever 27 is extended and formed with a hook 28. A stiff wire or rod 32 extends from each arm of the lever 27 to the latch members 20 and is attached to the latch member 20 at the lower end of the side member 21, so that rocking movement of the lever 27 will retract the latch members 20 against the force of the spring 24.

Another elongated lever 29 is rockably supported from the support plate 26 below the base plate 14. One arm of the lever 29 extends outwardly through the opening 17 and within the offset 18 to form a handle 30. The other end of the lever 29 extends inwardly and upwardly through the opening 15 in the base plate 14 and is engageable with the hook 28 of the lever 27. A lug 31 extends downwardly from the lever 29 and engages in the hook 28 of the lever 27.

In the normal position of this latching mechanism, the latches 20 project from the side walls 12 being held in this position by the spring 24. To unlock the latches 20, the handle 30 is rocked to engage and rock the lever 27. As the lever 27 is rocked, the rods 28 pull the latches 20 in against the spring action. By releasing the handle 30, the springs 24 again move the latches 20 outwardly into the projecting or latching position.

The exact configuration illustrated is regarded as the optimum, but some of the desirable results inherent in this disclosure may be obtained by various slight modifications including some departure from the exact configuration shown, and it is therefore requested that the scope of the invention should be regarded as limited only by the terms of the claim.

What I claim is:

A grave vault base comprising a horizontal top wall, depending side and end walls on said top wall, outwardly extending flanges parallel to said top wall extending from the lower end of said side and end walls, said flanges on the end walls formed intermediate the length thereof with downwardly offset portions parallel to said flanges and said end walls provided with openings above said offset portions, spring-pressed latches hingedly mounted on said side walls and extensible therethrough, a lever rockably mounted midway the length thereof between a pair of latches on opposite side walls for swinging in a horizontal plane parallel to said top wall rods connecting said latches and said lever, a hooked extension on one end of said lever, a second lever rockably mounted for horizontal swinging movement, a lug on one end of said second lever engageable with said hooked extension, and a handle on said second lever opposite from said lug extending through the opening in an end wall and disposed in said offset portion of an end wall flange for rocking said latches upon actuation thereof.
